FAUCET CONSTRUCTION

Earl J. Housekeeper and Carl J. Braun, Wooster,
Ohio, assignors to The Wooster Brass Company,
Wooster, Ohio, a corporation of Ohio

Application July 5, 1947, Serial No. 759,096

4 Claims. (Cl. 299—84)

1

The invention relates generally to faucets for dispensing carbonated beverages, and more particularly to novel means for dispensing a carbonated beverage with a high carbon dioxide content.

It is desirable to dispense carbonated beverages in such manner as to retain a high percentage of carbon dioxide in the beverage as it passes through and is discharged from the faucet into the glass, in order to improve the taste of the carbonated beverage.

Certain prior faucets have been designed to dispense carbonated water and syrup separately and simultaneously from the same spout to be mixed in the glass, and a faucet of this type is shown in U. S. Patent No. 2,401,914, issued June 11, 1946, to Carmelo V. DiPietro. In the copending application Serial No. 752,391, filed June 4, 1947, and entitled Dispenser Faucet Construction, we disclose a faucet for selectively dispensing carbonated water or syrup alone, or both simultaneously and separately.

In these faucets, and in certain other types, it has been attempted to provide some means for reducing the velocity and pressure of the carbonated water as it passes through the faucet, and for discharging it in a smoothly flowing condition with a relatively high carbon dioxide content, but such means have heretofore been only partially satisfactory for several reasons. For example, where the carbonated water is led through a plurality of very fine ports for diffusing the liquid to aid in reducing its velocity and pressure, after a period of use the fine ports become clogged with foreign particles inevitably existing in the carbonated liquid supply. Furthermore, such prior velocity reducing or diffusing means have had the further disadvantage of causing dripping of the carbonated liquid after the faucet is shut off, and this condition is undesirable.

The present invention has the general object of providing novel and improved means for dispensing carbonated liquids.

More specifically, it is an object of the present invention to provide a novel faucet having diffusing means for reducing the velocity and pressure of the carbonated liquid so as to discharge it in a smoothly flowing condition.

Another object is to provide a faucet which has novel means for discharging carbonated liquid in such manner that it retains a high content of carbon dioxide during the discharge of the liquid from the faucet and while it is filling a glass.

These and other objects are accomplished by the parts, elements, constructions and arrangements comprising the present invention, the na-

2

ture of which is set forth in the following general statement, preferred embodiments of which are set forth in the following description and shown in the accompanying drawings, the invention being particularly and distinctly pointed out and defined in the appended claims.

In general terms, the present invention comprises a faucet body including a discharge nozzle having downwardly converging walls merging with a cylindrical discharge outlet, the body having a carbonated liquid discharge outlet communicating with the upper end of the nozzle, and an annular diffusing tube horizontally disposed in the nozzle closely adjacent to its interior wall and connected to the discharge outlet, there being a plurality of radially directed ports in the outer upper wall of the annular tube and having a relatively large total area for discharging the liquid at greatly reduced velocity onto the nozzle walls.

20 Referring to the drawing forming part hereof in which preferred embodiments of the invention are shown by way of example:

Figure 1 is a side view, partly in elevation and partly in section, of the improved faucet construction having one embodiment of novel diffusing means therein;

Fig. 2 is a vertical sectional view partly in elevation, as on line 2—2, Fig. 1;

Fig. 3 is a detached side elevational view of said one embodiment of novel diffusing means;

Fig. 4 is a transverse sectional view thereof as on line 4—4, Fig. 3;

Fig. 5 is a vertical sectional view thereof, partly in elevation;

Fig. 6 is a detached side elevational view, similar to Fig. 3, of another embodiment of the novel diffusing means;

Fig. 7 is a transverse sectional view thereof as on line 7—7, Fig. 6; and

Fig. 8 is a transverse sectional view thereof, partly in elevation.

Similar numerals refer to similar parts throughout the several views of the drawing.

The improved dispenser faucet preferably has a hollow body or housing 10 in which a valve seat member 11 is secured, and the member 11 is preferably of corrosion-resistant metal such as stainless steel. The supply tubes carrying the liquids to be dispensed from storage reservoirs to the faucet are preferably bendable tubes or corrosion-resistant metal, and may include a carbonated water supply tube 12 and a syrup tube 13. These tubes have their inner ends seated in the member 11, and preferably the inner ends of the tubes 55 are outwardly flared as indicated at 14 and tightly

fitted in the sockets in the body member 11 by means of sleeve nuts 15 engirdling the tubes and screwed into the sockets.

The tubes 12 and 13 communicate with angular ports 17 and 18 respectively, located in seat member 11 and terminating at the seating face 19 of the member 11, and a rotary valve member 20 slidably abuts the seating face 19. A gasket may be interposed between the abutting faces of the seating member 11 and the valve member 20, but in the embodiment shown, the abutting surfaces are accurately ground to give a very tight sliding fit which eliminates the necessity of using a gasket.

The rotary valve member 20 is provided in a suitable manner with passageways for selectively connecting the ports 17 and 18 with a carbonated water discharge outlet 21 and a syrup discharge outlet 22, whereby syrup and carbonated water may be discharged through the nozzle 23, either one alone or both at the same time. The port arrangement within the valve member 20 may be the same as or similar to the port arrangement described and claimed in my copending application Serial No. 752,391.

The means for rotating the valve member 20 preferably includes a handle 24 screwed into a boss 25 on an arcuate guide portion 26 which fits movably around the valve housing 10. The guide portion 26 has an arm 27 connected to a socket member 28, and the valve member 20 is non-rotatably held in the socket member by means of a pin 29, so that rotary movement of the handle 24 will rotate the valve member 20. Rotary movement of the valve is limited by stop shoulders 30 and 31 on the housing 10, and the various positions of the valve for selective flow are located between the limits of movement defined by these shoulders. The intermediate position, which is shown in Figs. 1 and 2, may be the shut-off position of the faucet, and the several selective flow positions may be determined by a spring pressed ball 32 mounted in boss 25 for frictionally engaging any one of several indentations 33 in the housing 10.

As shown in Figs. 1 and 2, a syrup discharge tube 34 is preferably screwed into the faucet body for communication at its upper end with the syrup outlet port 22, and the syrup tube extends downward axially of the nozzle 23 and terminates at or just below the discharge end of the nozzle, for carrying the syrup through the nozzle without contacting the carbonated water until it enters the glass. The carbonated water outlet 21 is laterally or radially spaced from the syrup outlet 22 and enters the upper end of the nozzle at one side of the syrup tube.

The parts thus far described are substantially the same as corresponding parts in my copending application, Serial No. 752,391, and per se form no part of the present invention.

The nozzle 23 includes a spout 35 having its upper end 36 screwed into the depending annular portion 37 of the faucet body, and the inner surface 38 of the spout is preferably downwardly converging and terminates in a substantially straight cylindrical portion 39 of relatively small cross sectional area. Preferably, the bottom end of the spout has an outer lip 40 formed thereon for retaining a rubber bumper ring 41 thereon.

The novel means for reducing the velocity and pressure of the carbonated liquid, and discharging it onto the inner surface of the spout in a smoothly flowing condition, preferably comprises the tubular diffuser ring indicated at 42. The

ring has a substantially vertical or upright tube 43 which fits tightly into the outlet sleeve 43' in the faucet body, and may be secured therein as by brazing if desired. The bottom end of the upright tube 43 communicates with the interior of the horizontally disposed tubular ring 42, and may be secured thereto as by soldering or brazing. Preferably, the ring is formed from corrosion-resistant metal tubing and the cross sectional area of the tubular ring 42 is somewhat larger than that of the upright tube 43 so that as the carbonated liquid passes from the tube 43 into the larger tube 42, its velocity and pressure will be somewhat reduced.

Means for further reducing the velocity and pressure of the carbonated liquid, and for conducting it onto the internal surface 38 of the nozzle in a smoothly flowing condition, preferably includes a circumferential series of radially outwardly directed ports 44 in the outer wall of the tubular ring 42. The combined area of these ports is several times that of the cross sectional area of the ring, so that as the carbonated liquid discharges laterally through all of the ports 44, a substantial reduction in velocity and pressure of the liquid is effected. The area of each individual port 44 is sufficient to prevent clogging therein of foreign particles ordinarily existing in the carbonated liquid.

As indicated, the ports 44 are located in the upper portion of the exterior of the tubular ring 42, so as to form a reservoir of substantial size in the bottom of the ring. The purpose of this reservoir is to catch and retain any excess liquid in the outlet tube 21 and upright tube 43 when the carbonated liquid is shut off by the valve 20, so that no dripping of the liquid from the ring 42 will occur.

In the embodiment of Figs. 6, 7 and 8, the tubular ring 42a is constructed of two similar halves of non-corrosive metal 42b and 42c, which are brazed or otherwise secured together in opposing relation at the joint 46, and which have registering axial openings 47b and 47c for fitting around the syrup tube 34. The upper half 42b of the ring has an upright tube 43a for fitting in the outlet tube 44 in the faucet body, and the upper half 42b of the ring also has a circumferential series of radially directed ports 44a in its outer wall, similar to the ports 44 in the tubular ring 42.

As shown in Fig. 2, the rotatable valve 20 is adjustably held against the ground seating surface 19 by an adjusting screw 49 threaded through socket member 28, and preferably having a lock nut 50 thereon. The screw 49 and nut 50 are accessible through a hole 51 in the cap 52 screwed on one side of the housing 10. A similar cap 53 is preferably screwed on the opposite side of the housing, and covers a regulating valve for the syrup passageway 22, said valve including a stud 54 movable across said passageway and threaded through a bushing 55 screwed into the seating member 11.

In the operation of the improved faucet, when the rotary valve member 20 is operated to connect the carbonated water supply 12 with the carbonated water outlet 21 to dispense carbonated water, either alone or in combination with the syrup from the syrup supply tube 13, the carbonated liquid will flow into the outlet sleeve 43' at high velocity and pressure. In flowing from the upright tube 43 into the diffuser ring 42, a substantial reduction in velocity and pressure of the liquid is accomplished because of the greater cross sectional area of the tubular ring

42, so that the ring becomes a velocity-reducing chamber. As the carbonated liquid discharges laterally from the ring out through the ports 44, the velocity is further reduced because of the relatively large total area of the ports as compared with the cross sectional area of the ring, and the carbonated liquid is diffused or broken up into a plurality of outwardly directed streams.

Due to the close proximity of the outer surface of the tubular ring 42 to the upper part of the converging internal wall 38 of the nozzle, the streams are conducted onto the surface 38 in a smoothly flowing condition without appreciable loss of carbon dioxide. As these streams flow downwardly over the inwardly converging wall merging into the cylindrical surface 39, the liquid streams are directed vertically downward without causing any impingement of the stream particles, which would result in agitation and a release of carbon dioxide.

Accordingly, the carbonated liquid is dispensed or discharged into a glass held under the nozzle in a smoothly flowing condition with a relatively high carbon dioxide content, whether the carbonated liquid is being discharged alone, or whether syrup is simultaneously being discharged into the glass from the syrup tube 34. Furthermore, when the carbonated liquid is shut off at the valve 20, the flow into the nozzle is immediately stopped, so that no dripping of the carbonated liquid from the tubular ring 42 occurs.

Accordingly, the novel velocity-reducing, diffusing ring 42 or 42a provides a simple and inexpensive means of discharging the carbonated liquid in a smoothly flowing condition with a high carbon dioxide content; provides for eliminating substantially all dripping of the carbonated liquid when the supply of the same is shut off; and the cross sectional area of each of the ports 44 is sufficiently large to eliminate substantially all clogging thereof by foreign particles ordinarily existing in the carbonated water supply.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Having now described the invention, the construction, the operation and use, and preferred embodiments thereof, and the advantageous new and useful results obtained thereby; the new and useful constructions, and reasonable mechanical equivalents thereof obvious to those skilled in the art, are set forth in the appended claims.

We claim:

1. In a faucet having a discharge nozzle and a carbonated water outlet communicating with the upper end of said nozzle, a horizontally disposed annular diffusing tube located in the nozzle with its outer surface closely adjacent the interior surface of the nozzle, an upright tube of smaller cross sectional area than said annular tube and connecting said annular tube to said

outlet, and the outer wall of said annular tube having a series of radially directed ports therein, the combined areas of said ports being substantially greater than that of the cross sectional area of said annular tube, and said ports being spaced above the bottom wall of said annular tube to form a reservoir therein.

2. In a faucet having a discharge nozzle and a carbonated water outlet communicating with the upper end of said nozzle, a horizontally disposed annular diffusing tube located in the nozzle with its outer surface closely adjacent the interior surface of the nozzle, the interior surface of said nozzle converging downwardly below said diffusing tube and merging with a cylindrical discharge portion, means connecting said diffusing tube to said outlet, and the outer wall of said tube having a series of radially directed ports therein, the combined areas of said ports being several times that of the cross sectional area of said annular tube, said ports being spaced above the bottom wall of said annular tube to form a reservoir therein.

3. In a faucet having a discharge nozzle and a carbonated water outlet communicating with the upper end of said nozzle, a horizontally disposed annular diffusing tube located in the nozzle with its outer surface closely adjacent the interior surface of the nozzle, the interior surface of said nozzle converging downwardly below said diffusing tube and merging with a cylindrical discharge portion, an upright tube of smaller cross sectional area than said annular tube and connecting said annular tube to said outlet, and the outer wall of said annular tube having a series of radially directed ports therein, the combined areas of said ports being substantially greater than that of the cross sectional area of said annular tube, and said ports being spaced above the bottom wall of said annular tube to form a reservoir therein.

4. In a faucet having a discharge nozzle and a carbonated water outlet communicating with the upper end of said nozzle, a horizontally disposed annular element forming a diffusing tube located in the nozzle with its outer surface closely adjacent to the interior surface of the nozzle, a duct of smaller cross sectional area than said tubular element and connecting said tubular element to said outlet, and the outer wall of said tubular element having a series of radially directed ports therein, the combined areas of said ports being substantially greater than the cross sectional area of said tubular element.
